UNITED STATES PATENT OFFICE.

JAMES A. LIGHTBODY, OF WATERVILLE, MAINE.

BRAKE-LEVER SUPPORT.

No. 807,122.

Specification of Letters Patent.

Patented Dec. 12, 1905.

Application filed April 19, 1905. Serial No. 256,491.

To all whom it may concern:

Be it known that I, JAMES A. LIGHTBODY, a citizen of the United States, residing at Waterville, in the county of Kennebec and State of Maine, have invented a new and useful Improvement in Brake-Lever Supports, of which the following, taken in connection with the accompanying drawings, is a specification.

10 My invention relates to a device for supporting the levers that are pivotally connected to the cross-bar frame or truss that connects the two brake-shoes connected at their lower ends to brake-connecting rods and at their upper ends by the chain or rod that serves to operate the brakes; and it consists in attaching to the said cross-bar frame or truss inverted yokes, the upper parts of which serve as rests or supports for the said 15 levers.

This invention is illustrated in the accompanying drawings, in which—

Figure 1 is a plan showing one end of a truck-frame. Fig. 2 is a view, on a larger scale, drawn partly in end elevation and partly in section. Fig. 3 is a side view showing a part of the truck-frame, one of the wheels, and one of the brake-levers, its connected parts, and the inverted yoke that supports the lever.

In the drawings parts only of a truck are shown. The parts that do not relate to my device are omitted.

The frame of the truck is indicated by A, 35 the wheel by W W, the axle by B, the rails

by R R, and the brake-shoes, two of which are shown in Fig. 1, by S and S, one only being shown in Fig. 2. The brake-bar connection, which passes from one brake-shoe to the other, is a truss-frame consisting of 40 a main bar S' and inclined truss-bars T T, connected in the center to the coupling-piece T', which may be a part of the housing-piece H H', through a slot in which the brake-lever L passes. The said brake-lever L is pivoted at H² (see Fig. 3) in the usual manner.

As the brake device is usually constructed the lever L has no support above the housing-block H' and soon works loose, wears badly, and is liable to soon get out of good 45 working order. To remedy this defect, I have constructed the yoke-piece P P² P' and attached it to the members S' and T of the brake-bar truss by clamps, as shown. The upper part P² of the yoke forms a rest or support for the brake-lever L.

I claim—

A brake-lever support comprising an inverted yoke-piece attached to the brake-bar truss and constructed to support the brake-lever, substantially as and for the purpose set forth.

In testimony whereof I have signed my name to this specification, in the presence of two subscribing witnesses, on this 11th day 60 of April, A. D. 1905.

JAMES A. LIGHTBODY.
